CLAIM

The ornamental design for a dual chamber dispensing device, as shown and described.

DESCRIPTION

FIG. 1 is a front perspective view of a first embodiment of a dual chamber dispensing device.

FIG. 2 is a front elevation view of the dual chamber dispensing device of FIG. 1, the rear elevation view being identical to the front elevation view.

FIG. 3 is a right side elevation view of the dual chamber dispensing device of FIG. 1, the left side elevation view being identical to the right side elevation view.

FIG. 4 is a top plan view of the dual chamber dispensing device of FIG. 1.

FIG. 5 is a bottom plan view of the dual chamber dispensing device of FIG. 1.

FIG. 6 is an exploded front elevation view of the dual chamber dispensing device of FIG. 1.

FIG. 7 is a front perspective view of a liquid chamber and dispenser of the dual chamber dispensing device of FIG. 1.

FIG. 8 is a bottom perspective view of the liquid chamber and dispenser of the dual chamber dispensing device of FIG. 1.

FIG. 9 is a front elevation view of the liquid chamber and dispenser of the dual chamber dispensing device of FIG. 1, the rear elevation view being identical to the front elevation view shown in FIG. 9, it being understood that the front and rear elevation views of the liquid chamber and dispenser are identical to the views of the liquid chamber and dispenser shown in FIGS. 2 and 6, it being further understood that the right and left side elevation views of the liquid chamber and dispenser are identical to the view of the liquid chamber and dispenser shown in FIG. 3.

FIG. 10 is a top plan view of the liquid chamber and dispenser of the dual chamber dispensing device of FIG. 1.

(Continued)

FIG. 11 is a bottom plan view of the liquid chamber and dispenser of the dual chamber dispensing device of FIG. 1. FIG. 12 is a front perspective view of a frangible connector portion of the dual chamber dispensing device of FIG. 1, with the frangible material removed.

FIG. 13 is a bottom perspective view of the frangible connector portion of the dual chamber dispensing device of FIG. 1, with the frangible material removed.

FIG. 14 is a front elevation view of the frangible connector portion of the dual chamber dispensing device of FIG. 1, the rear, right side, and left side elevation views being identical the front elevation view shown in FIG. 14, it being understood that the front, rear, right side, and left side elevation views of the frangible connector portion are identical to the view of the frangible connector portion shown in FIG. 6. FIG. 15 is a top plan view of the frangible connector portion of the dual chamber dispensing device of FIG. 1, with the frangible material removed.

FIG. 16 is a bottom plan view of the frangible connector portion of the dual chamber dispensing device of FIG. 1, with the frangible material removed.

FIG. 17 is a front perspective view of a second embodiment of a dual chamber dispensing device.

FIG. 18 is a front elevation view of the dual chamber dispensing device of FIG. 17, the rear elevation view being identical to the front elevation view.

FIG. 19 is a right side elevation view of the dual chamber dispensing device of FIG. 17, the left side elevation view being identical to the right side elevation view.

FIG. 20 is a top plan view of the dual chamber dispensing device of FIG. 17.

FIG. 21 is a bottom plan view the dual chamber dispensing device of FIG. 17.

FIG. 22 is an exploded front elevation view of the dual chamber dispensing device of FIG. 17.

FIG. 23 is a front perspective view of a frangible connector portion of the dual chamber dispensing device of FIG. 17, with the frangible material removed.

FIG. 24 is a bottom perspective view of the frangible connector portion of the dual chamber dispensing device of FIG. 17, with the frangible material removed.

FIG. 25 is a front elevation view of the frangible connector portion of the dual chamber dispensing device of FIG. 17, the rear, right side, and left side elevation views being identical the front elevation view shown in FIG. 25, it being understood that the front, rear, right side, and left side elevation views of the frangible connector portion are identical to the view of the frangible connector portion shown in FIG. 22.

FIG. 26 is a top plan view of the frangible connector portion of the dual chamber dispensing device of FIG. 17, with the frangible material removed.

FIG. 27 is a bottom plan view of the frangible connector portion of the dual chamber dispensing device of FIG. 17, with the frangible material removed.

FIG. 28 is a front perspective view of a dry chamber of the dual chamber dispensing device of FIG. 17.

FIG. 29 is a front elevation view of the dry chamber of the dual chamber dispensing device of FIG. 17, the rear, right side, and left side elevation views being identical the front elevation view shown in FIG. 29, it being understood that the front, rear, right side, and left side elevation views of the dry chamber are identical to the view of the dry chamber shown in FIG. 22; and,

FIG. 30 is a top plan view of the dry chamber of the dual chamber dispensing device of FIG. 17, it being understood that the bottom plan view of the dry chamber is identical to the view shown in FIG. 21.

In the drawings, details shown in broken lines form no part of the claimed design. The dash-dot lines in FIGS. 12, 15, 23, and 26 represent unclaimed lines on the frangible connector portion.
